UNITED STATES PATENT OFFICE.

THOMAS DAY CRAIG, OF ALBIA, IOWA.

DENTAL INSTRUMENT.

1,110,379.

Specification of Letters Patent. Patented Sept. 15, 1914.

Application filed January 17, 1914. Serial No. 812,791.

To all whom it may concern:

Be it known that I, THOMAS DAY CRAIG, a citizen of the United States of America, residing at Albia, in the county of Monroe and State of Iowa, have invented certain new and useful Improvements in Dental Instruments, of which the following is a specification.

The present invention relates to improvements in dental instruments, and is designed especially for use in the removal of crowns, bridges, bands, and all artificial surfaces affixed to teeth.

The primary object of the invention is the provision of an instrument of this character which may be manipulated with facility by the operator when the occasion arises, which is efficient, and which is capable of performing the functions required expeditiously and accurately.

The invention resides essentially in certain novel combinations and arrangements of parts whereby the dental instrument is made to operatively engage under the crown to be removed and further in the means by which the engaging parts are caused to remove the crown, as will be more clearly set forth and claimed hereinafter.

In the accompanying drawings I have illustrated one complete example of the physical embodiment of my invention constructed according to the best mode I have so far devised for the practical application of the principles of my invention.

While I have herein illustrated the instrument as adapted for removing a crown from a tooth, and shall describe only this one feature of the device, it will of course be understood that the device is capable of use in many other ways in dentistry which need not be described at this time.

Figure 1 is a side elevation of an instrument constructed according to my invention. Fig. 2 is a plan view of Fig. 1. Fig. 3 is what might be termed a front end elevation of the instrument showing its application to a tooth crown before removal of the crown. Fig. 4 is a underside plan view of the actuating lever for withdrawing the crown from the tooth. Fig. 5 is a perspective view of one of the movable clamping jaws of the device. Fig. 6 is an enlarged view of the screw which forms the pivot for the two

movements of the clamping jaws, showing in addition a retaining screw for the actuating lever. Fig. 7 is a perspective view of one of the heads of the device.

In the preferred embodiment of my invention as exemplified in the drawings I have utilized the principles of the common type of pliers or scissors in the pivoted handles 1 and 2 of which the screw or threaded pin 3 forms the coupling member. In Fig. 6 it will be seen that the pin 3 is formed with an annular disk 4 adapted to be seated in a recess in the lever arm 2, and is further provided with a spherical head or ball 5 with a kerf 6 therein, and an annular groove 7 between the head and disk as will be described.

The two levers 1 and 2 in addition to being operable by hand, are provided with a power operating device comprising the pivoted screw bar 8 which is swiveled at 9 in the lever arm 1 and is passed through an enlarged opening in the lever arm 2 and provided with a thumb nut 10 adapted to bear upon the outer face of the lever arm 2 when drawing the two arms together.

The short arms of the levers 1 and 2 are provided with duplicate heads 11 and 12, angularly disposed and depending from the levers at a spaced distance in order to provide an opening 13 of considerable size for convenience of the operator. Each of the heads is provided with a dovetail groove 14 extending from end to end of the head and open at top and bottom, and these grooves form mortises for guiding the tenons of the movable jaws 15.

The lower end of each head is forked or bifurcated and formed with jaws 11' and 12' adapted to grasp the tooth and be retained thereon as an anchorage during the operation of the device.

As seen clearly in Fig. 5 the movable jaws or clutches are metal bars T-shape in cross section crowned with a spherical head or ball 16 and formed with outwardly curved lower fingers 17 between which the tooth crown is to be clutched and then removed.

The jaws 15 are slidable in the mortises of the heads of the lever arms and they are moved by means of the spring pressed actuating lever 18 which is fulcrumed by means of the socket 19 in the arm over the ball or head 5 of the pivot screw 3. A set or re-

taining screw 20 (Fig. 6) is threaded into an opening in the lever 18 and engages in the annular groove 7 of the pin to lock the lever 18 against displacement from its fulcrum 5, but permits free leverage movement 5 of the lever.

The lever 18 is connected to the heads 16 of the jaws 15 through the medium of the separated grooves 21 formed in the forks 22 10 of the lever 18, and in Fig. 4 it will be seen that these grooves are on a circumference struck from the socket 99 as a center, and that, when required, the lever 18 may be 15 swung laterally upon the ball 5 as a pivot, as when attaching or detaching the lever 18 from the device.

The actuating lever 18 is operated or moved on its pivot 5 by means of a thumb nut 23 on the swiveled stem 24 which is 20 passed through an opening 25 in the end of the lever, and it will be seen in Figs. 1 and 2 that this stem is provided with a tubular T-head or sleeve 26, slipped over the screw bar 8 and through which the screw bar 8 is 25 free to move. In this manner the actuating lever is anchored on the screw bar of the lever arms, but the parts may be easily detached from each other when desired.

From the above description taken in connection with the drawings it is evident that 30 the instrument is capable of two distinct movements *i. e.* the clamping of the grasping jaws on the tooth and then the pulling or sliding movement of the engaged clutch 35 fingers 17 to withdraw the crown from the tooth. The former of these movements is accomplished by drawing the two lever arms 1 and 2 together by means of the nut wing, into the position of Fig. 3 to grip the tooth 40 as in a vise and form an anchor or support for the further movements of the operative parts of the device. The slideable jaws or 45 clutches are shown in just the proper position to dislodge the crown, and this dislodgment is accomplished by means of the actuating lever 18, which, through turning its wing nut is moved on its fulcrum and causes the slideable jaws to be moved and 50 guided through the slotted heads of the levers 1 and 2, and the fingers or claws of the slideable jaws engaging under the crown draw the crown from engagement with the tooth. The vise or clamping jaws may then 55 be loosened and the instrument withdrawn from the mouth carrying the dislodged crown with it as will be readily understood.

I do not wish to be understood as limiting myself to the precise constructions illustrated, as changes may be made within the 60 scope of my claims without departing from the spirit of my invention. As for instance the shape of the slideable jaws and their clutching claws may be changed, or other additional jaws may be provided to constitute a "set" adapted for interchangeable

use. The shape and size of the mortise and tenon construction may also be varied if desired, and other colorable change and modifications are contemplated in the physical embodiment of my invention.

Special attention is directed to the ball and socket fulcrum of the actuating lever by means of which the lever is permitted to have a freedom of movement on its fulcrum to adjust itself when operating to pull the crown from the tooth, and the feature involving the spherical heads on the slideable jaws having their connection with the actuating lever through the round grooves in the lever head or forks is especially meritorious for facilitating attachment and removal of the actuating lever in addition to coupling the jaws with the lever ends.

The grooves 21 are shaped to fit the round heads 16 so that the heads are not likely to 85 pull out and can be taken out only at either side of the head.

Having thus fully described my invention, what I claim is:—

1. The combination in a dental instrument 90 having pivoted lever arms and spaced angular depending heads thereon, of movable clutching jaws in said heads, and means for moving said jaws, for the purpose described.

2. The combination with a pair of pivoted 95 arms having spaced angular depending heads, of clutching jaws movable in said heads, and a lever mechanism for moving said jaws as described.

3. The combination with a pair of lever 100 arms formed with heads approximately at right angles thereto, slideable clutching jaws in said heads, a pivot for said arms, and a lever to actuate said jaws having its fulcrum on said pivot.

4. The combination with a pair of lever arms formed with heads at approximately right angles thereto, slideable jaws in said heads, a pivot for said arms having a fulcrum head, and an actuating lever for said 110 jaws having a socket and interlocked with said fulcrum head.

5. The combination with a pair of lever arms formed with slotted heads at approximately right angles thereto, slideable jaws in 115 said heads, and a pivot for said arms having a fulcrum head and annular groove, of an actuating lever having a socket over said fulcrum head, and a retaining pin engaging said groove.

6. In a dental instrument, the combination with clutching jaws movable with relation to the instrument, an actuating lever for said jaws, and a ball and socket fulcrum connection between said lever and instrument.

7. In a dental instrument, the combination with pivoted lever arms having heads at approximately right angles thereto, clutching jaws movable in said heads, and coupling 120

heads on said jaws, of an actuating lever having a slotted head operatively engaging said coupling heads.

8. In a dental instrument, the combination with pivoted lever arms having mortised heads at approximately right angles thereto, clutching jaws slidable therein and having tenons, and spherical coupling heads on said jaws, of a fulcrumed, actuating lever having a forked end and the forks having separated slots embracing said heads as described.

9. The combination in a dental instrument having pivoted lever arms and spaced heads at approximately right angles thereto there-

on, a screw bar hinged to one arm and passed through an opening in the other arm and a wing nut on said screw bar, slideable clutching jaws in said head, a spring pressed perforated actuating arm for moving said clutching jaws, a screw bar attached to the first mentioned screw bar and passed through said actuating arm, and a thumb nut thereon bearing against said arm. 20

In testimony whereof I affix my signature 25
in presence of two witnesses.

THOMAS DAY CRAIG.
